UNITED STATES PATENT OFFICE.

COLIN MACBETH, OF BIRMINGHAM, ENGLAND, ASSIGNOR TO THE DUNLOP RUBBER COMPANY, LIMITED, OF REGENTS PARK, LONDON, ENGLAND, A BRITISH COMPANY.

MACHINE FOR MAKING PNEUMATIC TIRE COVERS OR CASINGS.

Application filed January 3, 1922, Serial No. 526,831, and in Great Britain February 4, 1921.

This invention relates to machines for making pneumatic tire covers or casings (which machines are generally known as case making machines), and has particular reference to mechanism for rolling down the casing plies on the sides of a rotating core, comprising spinning or rolling down discs which are carried by arms pivoted on a reciprocating carriage or slide, the said arms and the discs carried thereby being adapted to be moved into an inoperative position away from the sides of the core at the end of the inward or forward movement of the slide and to be retained in the inoperative position during the outward or return movement of the slide.

According to this invention, the means for moving the pivoted arms and the discs into the inoperative position are so constructed and arranged as to move inward or forward with the slide, when the discs effect the rolling down of the plies, and at the end of the inward or forward movement of the slide, the said means partake of a slight forward or rearward movement relatively to the slide in order to exert a thrust or pull on the said pivoted arms to move the spinning down discs outwardly away from the sides of the core and retain them in this position during the outward or return movement of the slide. The said means for moving the pivoted arms and the discs into the inoperative position may be operated by the driving shaft which operates the means for reciprocating the slide and may comprise a plunger or rods adapted to move forward with the slide and to engage with projections on the said pivoted arms at the end of the forward movement of the slide in order to move the arms and the discs into the inoperative position and retain them therein during the return movement of the slide. The reciprocation of the slide may be effected by means of an oscillatory lever, and a similar lever may be employed for actuating a plunger which moves the pivoted arms and the discs into the inoperative position. Alternatively cranks or eccentrics on a rotating shaft may be employed for reciprocating the slide and moving the pivoted arms into the inoperative position as hereinafter more fully described. Means may be provided for enabling the rate of inward or forward move-

ment of the slide and the spinning down discs to be varied so that the discs may move at an initial high speed when laying or rolling down the plies near the crown of the core, and at a slow speed when laying the plies over the bead heels. For this purpose the oscillatory lever for reciprocating the slide may be formed with a curved or cam slot in which a roller or pin eccentrically mounted on a revolving disc or the like is adapted to engage, the shape of this slot being such that the required variable speed of inward movement is imparted to the slide and the spinning down discs.

In order that the said invention may be clearly understood and readily carried into effect, the same will now be described more fully with reference to the accompanying drawings, in which:—

Figures 1, 2 and 3 are respectively a sectional front view, a plan, and sectional end view of one construction of the improved means in which oscillatory levers are used for effecting the required movements.

Figures 4 and 5 are sectional front views of slightly modified construction.

Figure 6 is a diagram illustrating a modified construction of the oscillatory lever for producing a variable speed of radial travel of the spinning down discs during the operative stroke.

Figure 7 is a diagram hereinafter explained in connection with the modified construction of oscillatory lever illustrated in Figure 6.

Figures 8 and 9 are respectively a front view and a plan showing a construction in which a crank shaft is used for effecting the required movements.

Figures 10 and 11 are respectively a front view and a plan of a further modification.

Figure 12 is a plan showing one mode of maintaining the discs against the sides of the core.

Figure 13 is a sectional view including the oscillatory lever illustrated in Figure 6.

A represents a portion of the tire core which is supported on the rotary spindle of the case making machine and A' indicates a ply or plies thereon. B B are the spinning down discs rotatably mounted on brackets B' B' angularly movable on pins B² B² at the inner and forked ends of arms B³ B³

which are pivoted on pins B^4 B^4 on a slide C constrained to move towards and away from the core in suitable guides on a frame or base C' .

5 The position of the slide C is such that the spinning down discs carried thereby travel in a radial path relatively to the core when the slide is moved on the base C' .

In the example shown in Figures 1 and 10 2, a revolving crank disc D operated from a suitable rotary part of the machine, carries an eccentric bush having two portions D' D^2 of different diameters; the smaller portion D' fits in a longitudinal slot in a lever D^3 whose upper end is pivotally connected to the aforesaid slide C and whose lower end has an elongated slot in which is positioned a pin D^4 mounted in the said base or frame C' , this connection at the lower end of the 20 lever enabling the latter to oscillate and move longitudinally on the pin D^4 due to the rotary movement of the crank disc D and thus effect the reciprocation of the slide C . The said pin D^4 may be adjustable in 25 a slot C^2 in the said base in a direction parallel with the direction of movement of the slide thereby enabling the positions of the lever D^3 and the slide C to be varied to suit cores of different diameters. The larger 30 portion D^2 of the said eccentric bush fits in a slot in a second oscillatory lever D^5 whose lower end is mounted on the aforesaid pivot pin D^4 whilst the upper end of this lever may carry a roller D^6 which is adapted to 35 engage with a plunger D^7 carried by and slidably movable in a guide C^3 fixed on the aforesaid slide. The plunger D^7 carries at its forward end an adjustable head D^8 which at a predetermined moment is adapted to be 40 forced by the lever D^5 into contact with projections B^5 on the pivoted arms B^3 which carry the spinning down discs B . The larger portion D^2 of the eccentric bush is 45 so arranged as to cause the lever D^5 to lag behind the lever D^3 during the oscillatory movement of the two levers so that during the forward or inward movement of the slide, the plunger D^7 moves with the slide but not relatively thereto. During this 50 movement the discs B are maintained in contact with the ply or plies A' on the sides of the core A by any suitable or usual means which may comprise springs or weights connected directly or indirectly to the arms carrying the spinning down discs so that the 55 latter are maintained against the sides of the core. Figure 12 illustrates one construction in which the pivoted arms B^3 are provided with or have secured thereto projections or extensions B^6 to which are connected by means of cables, chains or the like G passing around pulleys H tension springs J that are secured to the carriage or slide C . The tension springs J tend to pull the 60 projections or extensions B^6 in a direction

away from each other so that the pivoted arms B^3 tend to move towards each other in order to maintain the discs B in contact with the plies on the sides of the core. In addition to spring means for maintaining the discs in contact with the sides of the core additional pressure means may be provided whereby the pressure with which the discs bear on the plies is increased as the discs pass over the beads, but this arrangement forms no part of the present invention and is described in Patent No. 1,565,176. Upon the spinning down discs B just passing the inner edges of the plies A' or the bead toes thereon the lever D^5 in continuing its forward movement pushes the plunger D^7 forward relatively to the slide C^3 so that its adjustable head D^8 engages with the projections B^5 on the arms B^3 carrying the spinning down discs thus 85 angularly moving the said arms B in such manner that the spinning down discs are moved away from the sides of the core; the mechanism is so arranged that the lever D^5 maintains the plunger head D^8 in contact with the said projections B^5 during the return or outward movement of the slide so that the spinning down discs are held well 90 away from the plies on the core during the return or outward stroke. When the forward or inward movement is about to take place again, the lever D^5 is so controlled by the portion D^2 of the eccentric bush engaging therewith, that it no longer maintains the plunger head D^8 in engagement with the 95 said projections B^5 on the arms B^3 thus allowing the latter to assume the operative position in which the discs B make contact with the plies on the core.

In the modification shown in Figure 4, the 105 lever D^3 is formed at its upper end with a toothed segment D^{3x} in mesh with a toothed rack C^4 on the underside of the slide C , in this case the pivot pin D^4 at the lower end of this lever fits in a round hole in the 110 lever instead of an elongated slot as in the foregoing example.

In the further modification shown in Figure 5 the upper end of the lever D^3 is connected to the slide C through the intervention of a link D^9 and the upper end of the 115 lever may also be connected to the aforesaid plunger D^7 by means of a link D^{10} .

Instead of using an oscillatory lever D^3 with straight slot as shown in Figures 1, 4 120 and 5 for effecting the inward or spinning down stroke of the discs B , the oscillatory lever D^3 may be provided with a curved slot 1^a in which the roller D^6 works; by 125 means of this curved slot it is possible to vary the speed of radial travel of the spinning down discs during the operative or spinning down stroke in such manner that the discs initially travel at a high speed over the casing from near the crown, the speed 130

being gradually reduced as the discs travel over the sides of the casing until they are travelling at a comparatively slow speed at the bead heels where folding over the ply 5 requires careful operation in order to avoid creasing at this point. The straight slot in the levers D^3 shown in Figures 1, 4 and 5 does not permit of this speed variation and therefore the speed of the discs during the 10 inward radial movement is mainly determined by and has to conform with the slow speed required at the beads. By using the lever D^3 with the curved slot 1^a the complete inward travel can be performed more 15 quickly by reason of the initial rapid speed that can be imparted to the discs.

Figure 7 shows a curve a, b, c, d of which the vertical ordinates represent the radial velocity of the spinning down discs in relation 20 to the casing A' of which one side or half is shown under the said curve. It will be observed from the curve that at the commencement of the stroke indicated at a the speed of the discs increases very rapidly to 25 maximum at the point b and then gradually decreases during the travel along the sides of the casing until reaching the bead heel at c where the speed is very low to permit of the ply being folded over without creasing, 30 after which the speed increases to point d . At the commencement of the inward stroke, the lever D^3 and the roller D' are in the position shown by dotted lines at the left in Figure 6 and as the roller in moving round its circular path indicated by ω leaves the 35 curved face 1^b of the curved slot the velocity rapidly increases to its maximum as indicated at b in the diagram shown in Figure 7, when the face 1^c of the curved slot is approximately at right angles to the path of travel of the roller D' . From this point the 40 velocity gradually decreases as the roller D' moves down the face 1^c and on reaching the position shown by dotted lines at the right in Figure 6 the face 1^c is nearly tangential to the circular path of travel of the roller when the velocity is very low this 45 being at the point c on the aforesaid curve shown in Figure 7 where the spinning down discs are just travelling over the beads. After this an increased velocity is produced 50 by the roller D' engaging with the curved face 1^b . Thus the inward stroke is completed and the return stroke is similar to that obtained with the straight slotted lever 55 shown in Figures 1, 4, 5, as the lower portion of the curved slot 1^a is made straight. The type of lever shown in Figure 6 although 60 particularly suitable for beaded edge covers or casings may be used with advantage on straight side covers as by retarding the speed of radial travel of the spinning down discs over the bead a better consolidation of the latter is effected whilst the complete cycle

of operations can be accomplished more 65 quickly than with the straight slotted lever.

The example shown in Figures 8 and 9 show a modification in which the aforesaid oscillatory levers D^3, D^5 are not used; in this case the reciprocation of the slide C and 70 the actuation of the arms B^3 carrying the spinning down discs B is effected by means of a three throw crank shaft E rotatably mounted on a plate or frame C^5 on which the slide C carrying the arms B^3 supporting 75 the spinning down discs B is slidably mounted. The frame C^5 on which the crank shaft E is mounted is capable of adjustment on the base C' so that the whole spinning down mechanism can be readily adjusted to 80 suit cores of various diameters. The crank shaft E is rotated by a gear wheel E^5 driven in any appropriate manner and by means of a rod E connected to the medial crank of the shaft E it imparts reciprocation to 85 the slide C . The two outer cranks of the said shaft E are connected by means of pull rods E^2 to projections B^5 on the arms B^3 carrying the spinning down discs and the angular positions of the cranks are so arranged that upon the spinning down discs completing the inward or forward stroke, the outer cranks cause the pull rods E^2 to 90 act and open out the said arms B^3 thus moving the spinning down discs out of contact 95 with the sides of the core. The pull rods E^2 may have adjustable collars E^3 which bear against the projections B^5 on the said arms B^3 .

In the further modification shown in Figures 10 and 11, instead of using a three throw crank shaft, there is employed a shaft F driven by gearing F^5 and having end cranks which through suitable rods F^2 connected to the slide C impart the reciprocatory movement to the slide C . The said shaft F has an intermediate eccentric F^3 which may be connected by a rod F^4 to the plunger D^7 having an adjustable end D^8 which is adapted to engage with the projections B^5 on the disc arms at the end of the inward stroke to move the spinning down discs out of contact with the core and to maintain them in this position during the return stroke. 100

The base C' on which the spinning down mechanism is mounted may be positioned below the axis of the core spindle and it may be so inclined that the spinning down discs reciprocate in a radial path at an angle of 105 about 45 degrees to the vertical. 115

Instead of using single spinning down discs at each side of the core two discs for example a spinning down disc and a driving disc as described in the specification of my application No. 526,091, filed December 31st, 1921 may be caused to travel along each side of the core by the reciprocating means hereinbefore described. 120 125

What I claim and desire to secure by Letters Patent of the United States is:—

1. Spinning down mechanism for tire making machines comprising a reciprocating carriage, arms pivotally mounted on the carriage, discs carried by said arms and adapted to act on the plies of the tire as the carriage moves forward, and means movable with the carriage and adapted at the end 10 of each forward movement thereof to have an additional movement in the direction of the line of travel of the carriage to effect relative movement between the carriage and said arms to move the discs away from the 15 casing plies and retain them in an inoperative position during return movement of the carriage.
2. Spinning down mechanism for tire making machines comprising a reciprocatory carriage, arms pivoted on said carriage, spinning down discs carried by said arms, means movable with the carriage and adapted at the end of each forward movement thereof to have an additional movement in 20 the direction of the line of travel of the carriage for moving the arms and discs into an inoperative position, and a driving shaft adapted to actuate both the means for reciprocating the carriage and the means for moving the arms and discs into inoperative 25 position.
3. Spinning down mechanism for tire making machines comprising a reciprocatory carriage, arms pivotally mounted on said carriage, spinning down discs carried by said arms, members for reciprocating the carriage, plunger-like means adapted to effect movement of the pivoted arms to carry the discs to inoperative position, and reciprocating members for actuating the plunger-like means at the end of each forward movement of the carriage, for the purpose described.
4. Spinning down mechanism for case making machines as set forth in claim 1 in which a plunger or rod for engaging with the arms carrying the spinning down discs moves with the carriage until it reaches the end of its inward stroke, whereupon relative 45 movement between said plunger or rods and the slide takes place so that the arms carrying the spinning down discs are moved into the inoperative position substantially as described for the purpose specified.
5. Spinning down mechanism for tire making machines comprising a reciprocating carriage, arms pivotally mounted on the carriage, spinning down discs carried by said arms and adapted to act on the plies of the tire as the carriage moves forward, a plunger 55 engaging the arms carrying the spinning down discs, said plunger adapted to move with the carriage until it reaches the end of its inward stroke, whereupon relative move-

ment between said plunger and the carriage takes place, so that the arms carrying the spinning down disc are moved into inoperative position, an oscillatory lever actuated by a crank disc for imparting reciprocating motion to the carriage, and a second oscillatory lever for engaging said plunger and operatively associated with said first mentioned lever.

6. Spinning down mechanism for tire making machines comprising a reciprocatory carriage, arms pivotally mounted on said carriage, spinning down discs carried by said arms, and means movable with the carriage and adapted at the end of each forward movement thereof to have an additional movement in the direction of the line of travel of the carriage for reciprocating the carriage at a variable speed, the parts being so proportioned that during forward travel of the carriage speed increases rapidly to 75 the mechanism and then gradually decreases during the travel of the discs along the sides of the tire casing toward the beads over which the discs travel slowly.

7. Spinning down mechanism for tire making machines comprising a reciprocatory carriage, arms pivotally mounted on said carriage, spinning down discs carried by said arms, an oscillatory lever for reciprocating the carriage, a revolving member for oscillating said lever, a second oscillatory lever actuated by said revolving member, a plunger slidably mounted on the carriage and connected to the second oscillatory lever, and means whereby the plunger will engage the pivoted disc carrying arms at the end of the operative stroke of the carriage so as to move the discs into an inoperative position.

8. Spinning down mechanism for tire making machines as set forth in claim 7, in which the oscillatory lever for reciprocating the carriage is provided with a cam surface, an eccentrically mounted projection on the revolving member engaging said cam surface, the latter being so shaped that a variable speed is imparted to the spinning down discs and carriage during forward movement of the latter.

9. Spinning down mechanism for tire making machines comprising a reciprocatory carriage, arms pivotally mounted on said carriage, spinning down discs carried by said arms, a rotary shaft, crank or eccentric-like means operated by said shaft for reciprocating the carriage, reciprocating means on the carriage adapted to co-operate with the pivoted disc carrying arms to move said arms and discs into an inoperative position, and means operated by said shaft for actuating the last said means at the end of the operative or forward stroke of the carriage.

COLIN MACBETH.
